US0D1019033S

(12) **United States Design Patent** (10) **Patent No.:** **US D1,019,033 S**
(45) **Date of Patent:** **** Mar. 19, 2024**

(54) **DISHWASHER**

(71) Applicant: **LG ELECTRONICS INC.**, Seoul (KR)

(72) Inventors: **Suhyeon Son**, Seoul (KR); **Miyoung Kim**, Seoul (KR); **Wonjun Lee**, Seoul (KR)

(73) Assignee: **LG ELECTRONICS INC.**, Seoul (KR)

(**) Term: **15 Years**

(21) Appl. No.: **29/784,837**

(22) Filed: **May 21, 2021**

(30) **Foreign Application Priority Data**

Nov. 24, 2020 (KR) 30-2020-0057083

(51) **LOC (14) Cl.** **15-05**

(57) **CLAIM**

The ornamental design for a dishwasher, as shown and described.

DESCRIPTION

FIG. 1 is a front perspective view of the dishwasher showing our new design;

FIG. 2 is a front view thereof;

FIG. 3 is a back view thereof;

FIG. 4 is a left view thereof where the right view is a mirror image;

FIG. 5 is a top plan view thereof;

FIG. 6 is a bottom plan view thereof; and,

FIG. 7 is a partial enlarged view of a portion of FIG. 1. The broken lines depict portions of the dishwasher that form no part of the claimed design.

1 Claim, 7 Drawing Sheets
